ATTORNEY

UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed February 23, 1922. Serial No. 538,543.

To all whom it may concern:

Be it known that I, THOMAS A. REID, a citizen of the United States, and a resident of Wilkinsburg, in the county of Allegheny and State of Pennsylvania, have invented a new and useful Improvement in Electric Furnaces, of which the following is a specification.

My invention relates to electric furnaces and particularly to electric-resistance furnaces, and it has for one of its objects to provide a relatively simple furnace construction for electric-resistance furnaces.

Another object of my invention is to provide a relatively simple and inexpensive means for interlocking a plurality of thin refractory plates constituting the muffle of the furnace, to prevent relative movement thereof during the operation of the furnace, while permitting the quick removal of the refractory plates whenever necessary.

In practising my invention, I provide a furnace chamber defined by a plurality of spaced walls of refractory material, with a plurality of thin refractory plates, serving as the muffle or lining of the furnace and also as a resistor-supporting means, and I provide a plurality of refractory members, of substantially Z-shape in lateral cross-section, for interlocking with the edge portions of the thin refractory plates to maintain them in their proper operative positions in the furnace chamber.

In the single sheet of drawings,

Figure 1 is a view, in vertical lateral cross-section, of an electric-resistance furnace comprising the device embodying my invention;

Fig. 2 is a view, in horizontal lateral cross-section, of a pit-type electric-resistance furnace comprising the device embodying my invention;

Fig. 3 is a fragmentary top plan view of a heating element employed in my electric-resistance furnace, and

Fig. 4 is a view, in perspective, of a member of Z-shape embodying my invention.

An electric-resistance furnace 11 comprises an outer metallic casing 12 having a plurality of supporting members 13 suitably secured thereto. An outer lining 13 comprises a plurality of bricks or blocks of any suitable heat-insulating material located within the metallic casing 12. An inner lining 14 comprises a plurality of

bricks or blocks of any suitable high-temperature-resisting material, the bricks or blocks of the two linings being so shaped and located as to provide a furnace chamber 15 of any suitable or desired dimensions. The furnace structure thus far described is intended to be representative only and to illustrate a furnace with which certain members hereinafter to be described may be operatively associated.

A plurality of relatively thin refractory plates 16 comprise the muffle or lining of the furnace chamber, each of the plates 16 being substantially rectangular in contour and having a plurality of relatively small spaced-apart, alined, integral projections 17 on one surface thereof. That surface of the plate upon which are located the projections 17 is so placed as to face the inner lining 14 in order that the relatively smooth surface of the plates 16 may be immediately adjacent to the chamber 15.

A resistor member 18 comprises a rod or bar of a suitable metallic material pre-formed to comprise a plurality of substantially parallel-extending end-connected convolutions, substantially as illustrated in Fig. 3 of the drawing. The resistor member 18 operatively engages the surface of the plates 16 with the convolutions of the resistor member extending between the adjacent rows of alined projections 17. The plate 16 and the resistor member 18 constitute the heating element of my electric furnace and are more particularly described and claimed in application Serial No. 449,685, filed March 5, 1921, by O. A. Colby and myself and assigned to the Westinghouse Electric and Manufacturing Company. In that application, the plates 16 are illustrated as being provided with edge portions having a groove thereon to provide, in effect, a shoulder near the edge portions of the plates. As the plate is relatively thin, there is a possibility of a breakage of the edge portions of the plates and a possible interruption of the operation of the furnace consequent thereto. I have found it desirable to so change the edge portions of the plates as to do away with the shoulder and to employ in place thereof, a securing or locking means now to be described.

A thin metallic or refractory member 19, of substantially Z-shape in lateral cross-section and substantially coextensive with

the length of the refractory plate with which it is to be operatively associated, is placed between the adjacent portions of each two plates 16, substantially as illustrated in Fig. 1 of the drawing. In this position, the end surface and an adjacent edge portion of each of the two plates 16 is operatively engaged by the member 19 when it is placed in the hereinbefore described position. In assembling the muffle or lining of the furnace, the plate 16 which is to be located on the bottom of the furnace is first placed in its proper operative position in the furnace, then two members 19 are placed thereon in position to engage the end surfaces and the edge portion at the top of the plate immediately adjacent the sides thereof, after which the two side plates 16 may be placed in their proper operative positions. Two members 19 may then be placed upon the side plates 16 in substantially the positions illustrated in Fig. 1, after which the top plate 16 may be placed in position, it being understood that resistor members 18 are located in their proper operative positions on each of the respective plates 16 before they are moved longitudinally of the furnace structure into their respective operative positions in the furnace chamber. In Fig. 2 is illustrated a pit-type of furnace in which the furnace chamber 15 extends substantially vertically. The furnace casing 12, the outer lining 13 and the inner lining 14 may be of substantially the same material as hereinbefore described in connection with the horizontal furnace illustrated in Fig. 1 of the drawing. As the thin refractory plates 16 now extend substantially vertically, the interlocking members 19 may be symmetrically placed with reference to the adjacent plates 16, as any one of the plates 16 may be first placed in its proper operative position in the furnace structure and the other plates 16 placed in their proper operative positions in sequence around the furnace chamber. While no supporting structure has been shown or indicated in Fig. 2 of the drawing, any suitable or required construction may be employed in any manner well known in the art.

The device embodying my invention thus provides a relatively simple and inexpensive means for so interlocking the adjacent edges of relatively thin refractory resistor-supporting plates as to maintain them in their proper operative positions in the furnace structure and relatively to each other during the operation of the furnace, while still permitting an easy and quick removal of any damaged refractory plate and its replacement by a new plate whenever this becomes necessary.

Various modifications may be made in the device embodying my invention without departing from the spirit and scope

thereof and I desire that only such limitations shall be placed thereon as are imposed by the prior art or are specifically set forth in the appended claims.

I claim as my invention:

1. In an electric furnace, in combination, a plurality of walls enclosing a furnace chamber, a plurality of relatively thin refractory plates constituting the lining of said chamber, and relatively thin, shaped, refractory members located between the adjacent edges of the refractory plates, and independent of said walls for maintaining them in proper operative positions relatively to each other. 70

2. In an electric furnace, in combination, a plurality of walls enclosing a furnace chamber, a plurality of relatively thin refractory plates constituting the lining of said chamber, and a refractory member out of contact with said walls for interlocking the thin refractory plates, said member being located between the adjacent edges of the plates. 80

3. In an electric-resistance furnace, in combination, a plurality of walls enclosing a furnace chamber, a plurality of relatively thin refractory plates constituting the lining of said chamber, the edges of said plates being located in spaced-apart overlapping relation and a single shaped refractory member operatively engaging one edge and one face of each of two adjacent plates to interlock the same. 90

4. In an electric furnace, in combination, a plurality of walls enclosing a furnace chamber, a plurality of relatively thin refractory plates constituting the lining of said chamber, and a plurality of relatively thin refractory members, of substantially Z-shape in lateral cross-section, for operatively engaging an end face and an adjacent edge portion of each of two refractory plates for maintaining the plates in proper operative positions relatively to each other. 100

5. In an electric resistance furnace, in combination, a plurality of walls enclosing a furnace chamber, of substantially rectangular contour in lateral cross-section, a plurality of relatively thin refractory plates constituting a lining for the walls of said chamber, the lateral width of said plates being substantially less than the lateral dimensions of said furnace chamber, and a plurality of relatively thin refractory members, of substantially Z-shape in lateral cross-section, for operatively engaging an end face and an adjacent edge portion of each of two refractory plates for preventing lateral movement thereof. 110

In testimony whereof, I have hereunto subscribed my name this 20th day of February, 1922.

THOMAS A. REID.
